RAILWAY CAR.

APPLICATION FILED DEC. 28, 1899.

3 SHEETS—SHEET 1.

FIG. 2.

This technical drawing illustrates a mechanical apparatus, possibly a printing press, through three main views (2.5, 2.6, 2.7) and two detailed views (15, 17). The main views show a large rectangular frame with various internal components, including a central vertical column and a horizontal beam. Numerous parts are labeled with numbers such as 18, 19, 25, 26, 27, 28, 29, 3, 5, 6, 9, 11, 12, 13, 14, 15, 22, 23, 24, 25, 26, 27, 28, 29, and 30. The detailed views (15 and 17) provide a closer look at specific mechanisms, including pulleys and connecting rods. The drawing is signed 'Hanford L. Kerr' and 'Inventor' in the bottom right corner.

UNITED STATES PATENT OFFICE.

HANFORD LESTER KERR, OF KANSAS CITY, KANSAS.

RAILWAY-CAR.

No. 818,629.

Specification of Letters Patent.

Patented April 24, 1906.

Application filed December 28, 1898. Serial No. 741,850.

To all whom it may concern:

Be it known that I, HANFORD LESTER KERR, a citizen of the United States, residing at Kansas City, in the county of Wyandotte and State of Kansas, have invented certain new and useful Improvements in Railway-Cars; and I do hereby declare the following to be a full, clear, and exact description of the invention, such as will enable others skilled in the art to which it appertains to make and use the same.

My invention relates to certain new and useful improvements in railway-cars, and particularly to that class of cars used for the transportation of fruits, vegetables, or other perishable cargoes, and has for its object to produce such a car in which a constant circulation of air at a predetermined temperature is provided.

This invention consists of an ordinary box-car being provided with a number of water-troughs with perforated coverings arranged longitudinally along the floor of the car and having steam or hot-water pipes passing therethrough. At either end of the car is a screen-partition, forming an end compartment which is provided with air-shafts leading from a screened opening near the top of the car to several fans discharging into the main body of the car. A suitable shaft is journaled in this compartment and is driven from the car-axle by means of a flexible belt and serves to operate the several fans before mentioned, as well as a pumping mechanism which is adapted to draw water from one of the troughs and spray it across the air-shafts at the screened opening.

With the above and other objects in view my invention further consists in the novel details of construction and combination of parts to be clearly described in the following specification and fully set forth in the claims.

Referring to the accompanying drawings, forming a part of this specification, in which like characters of reference indicate same parts throughout, Figure 1 is a vertical sectional view of a car embodying my improvements. Fig. 2 is a horizontal section on the line 2 2 of Fig. 1. Fig. 3 is a vertical cross-section of the car, taken on the line 3 3 of Fig. 1. Fig. 4 is an enlarged vertical section of the water-pump. Fig. 5 is a perspective view of a section of the flooring, showing the construction of the water-troughs and their coverings. Fig. 6 is a transverse section through an end trough, showing the elbow

feed and discharge connection; and Fig. 7 is a vertical section of one of the water-troughs at one of its partitions.

In the drawings, 1 represents the car-body, formed with double walls having a non-heat-conducting material, such as wool or the like, packed therebetween. Between the longitudinal carrying-beams 2 of the car are arranged a number of water pans or troughs 3, which have their upper edges turned outward and seated in rabbets along the upper edges of the carrying-beams. In these rabbets are also fitted pairs of transversely-slotted cover-plates 4, the upper one of each pair having a sliding fit between upturned flanges of the lower one and lying flush with the top surface of the carrying-beams. A series of steam-heating pipes 5 extends along the bottoms of the troughs and has suitable pipe connection with the engine, whereby the contents of the troughs may be heated by hot water or steam from the engine to maintain the proper temperature in the car during cold weather.

To prevent the water contained within the troughs from rushing to one end of the car when the car is starting or stopping, I provide at short intervals in each trough suitable vertical cross-partitions 6, having perforations therein which allow of a gradual flow of water therethrough, as is occasioned in filling or discharging, but which are sufficiently small to resist any sudden flow as that mentioned. The several troughs are in communication with each other by means of the pipe 7, which extends across the car and is tapped to the bottom of each trough.

For filling and emptying the troughs an elbow 8 is employed which is tapped to one side trough with a loose joint that it may be turned either in an upward direction to receive and retain water for the troughs or in a downward direction to discharge the water from the troughs. It will thus be seen that the troughs may be filled with water to a desired depth by pouring into the elbow the water passing from the first trough to all the other troughs through the pipe 7, thus being distributed over the bottom of the car and serving as a cooling agent in warm weather by its evaporation, the pairs of cover-plates being arranged with their perforations in register for this purpose.

As the air-circulating mechanism is the same at each end of the car, it is deemed sufficient for the purposes of this specification to describe that at one end only.

Near the end of the car a vertical wire-screen protecting-partition 9 is located, which extends entirely across the car and from the bottom, which to this line is closed nearly 5 to the top, forming an end compartment in which air is received at the front end of the car, passed through a spray of water to remove the dust particles, and then into the car-body proper, all by mechanism now to be 10 described.

A shaft 10 is mounted in suitable journals just above the floor of the car and receives its motion from the car-axle 11 by means of a flexible rope or cable 12, passing over 15 the pulleys 13 and 14 on the axle and shaft, respectively. To compensate for the rocking motion of the car, the pulley 14 is provided with a double groove, and the rope 12, after passing around one groove, suspends a 20 weighted pulley 15, free to move between the beams of the car, and then passes up and around the other groove of the pulley 14. Thus the swinging or rocking of the car on its trucks does not destroy the driving connection 25 between the axle and the shaft.

Depending from the roof of the car and extending from side to side thereof is a cross-partition 16 between the screen-partition 9 and the end of the car. This cross-partition 30 has a square cut-away portion in the middle of its lower end and has a pair of gutters 17, extending from about its center to near the lower corners, just escaping the square cut-away portion. A screened opening 18 is 35 formed in the end of the car just beneath the roof, through which air is admitted and deflected by the cross-partition 16 to the lower part of the compartment. A spray-pipe 19, located just beneath the screened opening 18, is 40 adapted to spray water in a thin sheet across the opening or air-passage between the end of the car and the cross-partition 16, and this water on striking the partition 16 and running down same is gathered by the 45 gutters 17 and conveyed by the pipes 20 back to the troughs. The water is fed to the spray-pipe 19 from one of the troughs by means of a pump 21, of ordinary construction, operated by an eccentric and strap 21' on the shaft 10 50 and connected with the spray-pipe by the pipe 22. This pump, as shown in Fig. 4, is of a common construction, with a cylinder *a*, plunger-piston *b*, inlet check-valve *c*, outlet check-valve *d*, and air-dome *e*.

55 A central air-shaft is formed by a pair of parallel side plates 23, extending from the top of the car as far down as the lower end of the cross-partition 16 and from the end of the car to an inclined plate 24, which slants 60 from the top of the screen-partition 9 to the bottom of the cross-partition 16, and these side plates are as far apart as the side edges of the square opening in cross-partition through which they pass. It will be seen that the 65 central air-shaft thus formed between the

side plates 23, inclined plate 24, the end of the car, and the cross-partition 16 is of V shape, the air passing in through the screened opening 18, between the side plates 23, down through the water-spray, then through the 70 square cut-away portion of the cross-partition 16, and up between the inclined plate 24 and the cross-partition 16, and finally discharging through the space above the screen-partition 9 into the car. To facilitate this 75 motion, a fan 25 is journaled in the central air-shaft above the inclined plate 24 and opposite the discharge-opening and is driven by a belt 26, connecting its pulley with a pulley 27 on the shaft 10 and passing through suitable perforations 28 in the inclined plate 24. The air admitted through the screened opening 18 on either side of the central shaft after passing through the water-spray flows down around the cross-partition 16 and out 85 through the screen-partition 9 into the body of the car, which movement is facilitated by the blast-fans 29, located on opposite sides of the car and operated by the shaft 10.

From the foregoing it will be seen that air 90 is taken in at the upper part of the forward end of the car, where it is divided to pass through a central shaft and side shafts and after being filtered through a fine spray of water is discharged forcibly into different 95 portions of the car-body, while similar mechanism at the rear end of the car, operating in an opposite manner, assists the circulation of air through the car by forcing it out at the rear.

A car as thus constructed is particularly well adapted for the transportation of fruits, vegetables, or other perishable cargo, as a constant circulation of fresh air is assured and the car maintained at the required temperature.

It is obvious that many changes may be made in the details of the arrangement and construction without departing from the spirit or scope of my invention.

What I claim as new, and desire to secure by Letters Patent, is—

1. In a device of the character described, a car-body having an air-opening in the end thereof, a V-shaped central air-shaft taking 115 air from the opening and discharging it in the upper part of the car, an air-fan located at the discharge end thereof side air-shafts also taking air from the opening and discharging beneath the discharge of the central air-shaft, a pair of fans for facilitating the passage of air through the side shafts and means connected with the car-axle for driving the several fans, substantially as described.

2. In a device of the character described, a 125 car-body, water-troughs located between the carrying-beams thereof, sliding perforated covers for the water-troughs, said car-body having an opening in its end, a central air-shaft taking air from the opening and dis- 130

charging it near the top of the car, side air-shafts also taking air from the opening and discharging it below the discharge of the central air-shaft, fans located in the several air-shafts, a shaft suitably journaled, means for driving the fans from the shaft, a pump operated by the shaft and adapted to take water from the troughs and spray it across the air-shafts, and gutters adapted to carry off water from the sprays and return it to the troughs, substantially as described.

3. In a device of the character described, a car-body having an air-opening in the end thereof, a V-shaped central air-shaft, taking air from the opening and discharging it in the upper part of the car, an air-fan located at the discharge end thereof, side air-shafts also taking air from the opening and discharging beneath the discharge of the central air-shaft, and a pair of fans for facilitating the passage of air through the side air-shafts.

4. In a device of the character described, a car-body, water-troughs located between the carrying-beams thereof and open to the interior of the car, said car-body having an opening in its end, a central air-shaft taking air from the opening and discharging it near the top of the car, side air-shafts also taking air from the opening and discharging it below the discharge of the central air-shaft, fans located in the several air-shafts, a pump adapted to take water from the troughs and spray it across the air-shafts, and gutters in the air-shafts to return the water to the troughs.

35 In testimony whereof I affix my signature in presence of two witnesses.
